UNITED STATES PATENT OFFICE.

JOHN HENRY KOCHOB, OF MCKEESPORT, PENNSYLVANIA.

REEL-HOLDER FOR MOVING-PICTURE MACHINES.

1,347,956.

Specification of Letters Patent. Patented July 27, 1920.

Application filed March 29, 1918. Serial No. 225,491.

To all whom it may concern:

Be it known that I, JOHN H. KOCHOB, a citizen of the United States, residing at McKeesport, in the county of Allegheny and State of Pennsylvania, have invented 5 certain new and useful Improvements in Reel-Holders for Moving-Picture Machines; and I do hereby declare the following to be a full, clear, and exact description of the invention, such as will enable others skilled in the art to which it appertains to make and use the same.

This invention relates to miniature moving picture machines and the primary object of the invention is to provide a support or holder for the upper film carrying reel of a miniature moving picture machine by means of which holder the reel may be supported in a film unwinding and projecting 20 position and by a slight rearward pivotal movement thereof the holder may be moved to engage the top of the moving picture machine to support the reel in an inoperative position.

More specifically, this invention comprehends the provision of a reel support as specified which is constructed of a single strand of wire bent to form reel shaft engaging eyes at the ends of the legs thereof 30 and to provide loops for engaging a shaft or pin carried by the top of the moving picture machine and downwardly curving leg portions for engaging a portion of the top of the machine to hold the reel in an operative 35 film unwinding position which loops, coacting with the lengths of the strands between the loops and the shaft carrying eyes for holding the reel in an inoperative position.

With the foregoing and other objects in view, this invention consists in such novel features of construction, combination and arrangement of parts as will be hereinafter more fully described, illustrated in the accompanying drawings and claimed.

In describing the invention in detail, reference will be had to the accompanying drawing, wherein like characters designate like and corresponding parts throughout the several views, and in which:

Figure 1 is a side elevation of a miniature moving picture machine showing the improved reel support applied thereto.

Fig. 2 is a top plan of the improved reel

support showing it applied to a fragment of a moving picture machine.

Fig. 3 is a fragmentary perspective view of the reel support.

Referring more particularly to the drawing, 1 designates a miniature moving picture machine of ordinary construction, the cover or top of which is indicated by the numeral 2 and carries a shaft 3. The top 2 is provided with a depending flange 4 which engages the top of the main body of the light projecting portion of the machine.

The improved reel holder, which is generically indicated by the numeral 5, is constructed of a single strand or length of wire bent to form two upstanding legs 6 and 7 which legs are bent to form inwardly extending angular portions 8 near their upper outer ends. Eyes 9 are formed upon the terminals of the angled portions 8 and these eyes are bent to lie parallel with the main portions of the legs 6 and 7, as clearly shown in Fig. 2 of the drawing. The eyes 9 rotatably support the shaft 10 which carries the reel 11 from which the film indicated at 12 is unwound during the projecting of the pictures. Loops 14 are formed at the lower ends of the legs 6 and 7 and the loops 14, which are substantially the shape of an inverted U, have their normally rear legs elongated and forming forwardly curving portions 15 which are connected by the length 16 of the wire. The length 16 of the wire is sinuously curved, being bent upwardly and rearwardly as shown at 17 to provide the portion 18 which is adapted to engage the ledge formed about the lower portion of the top 2 of the machine 1, as clearly shown in Fig. 2 of the drawing, when the reel 11 is in a film projecting or unwinding position.

When the reel 11 is supported in a forward outward position from which position the film 12 is unwound, the shaft 3 is engaged by the elongated legs 15 of the substantially inverted U-shaped loop 14, and the lower ends of these legs engage the forward edge of the flange 4, while the portion 18 of the holder engages the upper surface of the flange 4 or ledge intermediate of the two elongated legs 15, thereby rigidly supporting the reel 11 in its forward position.

When the reel 11 is not in use, it is moved

back over the top 2 of the machine 1, as indicated in dotted lines in Fig. 1 of the drawing. When the reel 11 is in its rearward inoperative position, the shaft 3 is engaged by the bight portion of the substantially inverted U-shaped loops 14, and the parallel lengths of the legs 6 and 7 engage the upper forward corner of the top 2, thereby rigidly supporting the reel in its rearward inoperative position.

In reducing the invention to practice, certain minor features of construction, combination and arrangement of parts may necessitate alterations to which the patentee 15 is entitled, provided such alterations are comprehended within the scope of what is claimed.

What is claimed is:

1. In a device of the class described, the combination with a body and a reel, of a support for the reel constructed of a single strand of wire bent to form shaft supporting eyes and engaging portions for engagement with a body to hold the reel in an operative position above and in advance of the body and in an inoperative position over the body.
2. In a device of the class described, the combination with a body and a reel, of a support for the reel constructed of a single strand of wire bent to form parallel legs, shaft supporting eyes at the upper ends of said legs, and engaging portions at the lower ends of the legs for engagement with the

forward end of the body to hold the reel in 35 an operative position above and in advance of the body.

3. In a device of the class described, the combination with a moving picture machine including a body and a reel, of a reel holder 40 constructed of a single strand of wire bent to form a pair of parallel extending spaced legs, shaft supporting eyes formed on the upper ends of said legs, substantially inverted U-shaped loops formed at the lower ends of said legs, the rearmost legs of said loops being elongated and curving outwardly over the loops for engagement with the upper end of the body, said elongated legs adapted to engage a portion of the body 45 intermediate their ends for coacting with the lower forward portions thereof in supporting the reel in an operative position, the portion of said wire intermediate said elongated forwardly curved legs being continuously bent to form a body engaging portion for coaction with the legs to the reel in an extended position, said loops and portions of said parallel spaced legs adapted to engage portions of the body to support a reel 50 in inoperative position.

In testimony whereof I affix my signature in presence of two witnesses.

JOHN HENRY KOCHOBÖ.
